UNITED STATES PATENT OFFICE.

LAWRENCE A. BUNDY, OF ATLANTA, KANSAS.

RAIL-JOINT.

No. 867,012.

Specification of Letters Patent.

Patented Sept. 24, 1907.

Application filed April 3, 1907. Serial No. 366,138.

To all whom it may concern:

Be it known that I, LAWRENCE A. BUNDY, a citizen of the United States, and a resident of Atlanta, in the county of Cowley and State of Kansas, have invented 5 a new and Improved Rail-Joint, of which the following is a full, clear, and exact description.

The present invention is directed to improvements in rail joints, preferably embodying features of construction of my improved rail joint for which Letters Patent 10 were granted me December 13, 1904, No. 777,239.

Among the objects of this invention is the provision of a rail connection that will insure a smooth road with no low joints, and in which the joints will be held against any accidental lateral displacement.

15 Reference is to be had to the accompanying drawings forming a part of this specification, in which similar characters of reference indicate corresponding parts in all the figures.

Figure 1 is a side view of a railway track embodying 20 my invention; Fig. 2 is a side view of a rail section with one of my improved chairs carried thereon as placed preparatory to connecting it with the next adjacent rail section; Fig. 3 is a side view of a rail section adapted to interlock with the section shown in Fig. 2; 25 Fig. 4 is a perspective, sectional view of one-half of a form of my improved joint; Fig. 5 is a cross section through a modified form of my invention; Fig. 6 is a face view of a locking plate forming a detail of construction, and Fig. 7 is a side view of two rail sections showing them in the position assumed in coupling them together.

My improved rail joint as preferably constructed, 30 comprises a rail 1 of the ordinary construction except at the opposite ends thereof where the web of the rail is thickened to make it of substantially the same width as the rail head, this construction being best illustrated in the perspective view, Fig. 4. At one end of each rail is a spur 2 of substantially the same construction as disclosed in my prior patent referred to, these 35 spurs being adapted to enter corresponding recesses formed in the opposing ends of the rails to which they are connected, the spurs being somewhat shorter than the depth of the recesses, to admit of expansion. The spurs of the adjacent rails are preferably oppositely 40 directed as shown in Figs. 2 and 3, in order that they may be easily assembled in the construction of the road.

After the rails are joined, a chair 3, which is slipped over one of the rails prior to the coupling operation, 45 is slid to bring it centrally of the rail joint. This chair

comprises a base-plate 4 having a corrugated under face and formed as an integral part with side-plates 5, the latter being so shaped as to closely embrace the flanges of the rail at opposite sides, and are each constructed with inwardly-directed top and bottom ribs 55 6 and 7, respectively, to engage with the thickened ends of the rail web at the top and bottom portions thereof, the flange 7 being preferably constructed with a sharp edge, as clearly shown in Figs. 4 and 5. The chairs 3 are preferably provided with notches 8, two at each 60 side of the rail for spiking them in place to the ties, the corrugations on the under face of the chair preventing any accidental lateral displacement of the joint. If desired, the chairs may be connected through the thickened portion of the abutting rails, by transverse bolts 9, in which case it is desirable to use four bolts for each chair, two passing through the adjacent ends of each rail, oblong openings or slots being provided in the chairs for the reception of the bolts whereby the rails may readily expand and contract when 70 connected at the joints. A locking-plate 10 shown in Fig. 6, is passed over each bolt before the nut thereon is screwed up, these locking plates comprising extending tongues 11 for embracing the nut at three sides, and a depending portion 12 for engaging with the chair 75 over the rail-flange, the manner in which these locking-plates are applied being clearly shown in Fig. 4.

In Fig. 5 is shown a modified form of my invention in which the webs of the rails, instead of being thickened at opposite ends as shown in Figs. 2, 3 and 4, are 80 provided with fish-plates 13, which fill out the space under the head of the rail and neatly conform to the under side thereof, as also to the top of the rail flanges, these plates being preferably longitudinally channelled on their inner faces, as shown.

Although the construction as hereinbefore described is my preferred form of invention, it is apparent that the same may be modified within the scope of the annexed claims.

Having thus described my invention I claim as new 90 and desire to secure by Letters Patent:

1. In a rail joint, the combination of two abutting rails having thickened webs and spur connections at their point of union, and a chair embracing the flanges and thickened webs of said rails.

2. In a rail joint, the combination of two abutting rails having thickened webs and spur connections at their point of union, a chair embracing the flanges and thickened webs of said rails, and bolts connecting the chair and rails together.

3. In a rail joint, the combination of two abutting rails having thickened webs and spur connections at their point

of union, a chair embracing the flanges and thickened webs of said rails, bolts having nuts connecting the chair and rails together, and locking plates for securing said nuts.

5 4. In a rail joint, the combination of two abutting rails having thickened webs at their point of union, and a chair composed of a base-plate and side-plates embracing the flanges and thickened webs of the rails, said side plates having inwardly directed ribs formed on their inner faces.

10 5. In a rail joint, the combination of two abutting rails

having thickened webs and spur connections at their point of union, and a chair comprising a base-plate having side plates formed integral therewith embracing the flanges and thickened webs of the rails.

In testimony whereof I have signed my name to this 15 specification in the presence of two subscribing witnesses.

LAWRENCE A. BUNDY.
